ADJUSTABLE PLUMB

John Woods, Montreal, Quebec, Canada

Application October 7, 1931, Serial No. 567,441
In Canada October 7, 1930

4 Claims. (Cl. 33—217)

This present invention relates to certain new and useful improvements in an adjustable plumb.

The primary object of the invention is the provision of an adjustable plumb which is of generally improved and simplified construction and increased efficiency.

The invention has for another object the provision of an adjustable plumb of the character stated which may be readily adjusted on the plumb supporting cord by winding more of the cord in the plumb bob or releasing more of the cord therefrom, thus making it unnecessary to make an adjustment of this character at the tripod or other supporting and suspending means for the plumb bob carrying cord.

The invention has for a further object the provision of an adjustable plumb of the character stated which is true and accurate in its operation with the plumb bob supported centrally on the cord at all times.

The invention has for a still further object the provision of an adjustable plumb of the character stated in which the plumb bob suspending cord has its lower end wound on a drum within the plumb bob with the drum automatically locked in its adjusted position and held against accidental rotation.

The invention has for a still further object the provision of an adjustable plumb of the character stated which is composed of the minimum number of parts of simple and inexpensive construction and arrangement and constructed in such a manner that the parts may be readily separated for inspection of the drum or mounting of the plumb bob depending cord on said drum or for other purposes, as desired.

The invention has for a still further object, the provision of an adjustable plumb of the character stated which is not only of increased efficiency and improved construction and operation but may be readily manufactured at small cost and retailed at a popular price with good profit, thus providing a commercially attractive proposition.

To the accomplishment of these and related objects as shall become apparent as the description proceeds, my invention resides in the construction, combination and arrangement of parts as shall be hereinafter more fully described, illustrated in the accompanying drawing and pointed out in the claims hereunto appended.

The invention will be best understood and can be more clearly described when reference is had to the drawing forming a part of this disclosure,

wherein like characters indicate like parts throughout the several views.

In the drawing:—

Figure 1 is an elevation of the improved adjustable plumb;

Figure 2 is a top plan view thereof; and

Figure 3 is a vertical longitudinal section through the adjustable plumb as taken on the plane of line 3—3 of Figure 1, looking in the direction indicated by the arrows.

Referring more in detail to the drawing, it will be noted that the adjustable plumb includes a plumb bob formed in upper and lower sections, the upper section 6 being solid with a depending threaded central extension 7 and a longitudinal central opening 8 through which extends the plumb bob suspending cord 9. The lower section 10 of the plumb bob terminates at its lower end in a central point 11, the lower half of the section 10 being tapered or beveled to inverted conical form. A well 12 is formed in the centre of the lower section 10 of the plumb bob and said lower section 10 is interiorly threaded at its upper end for removable threaded engagement on the depending threaded central extension 7.

Extending transversely through the well 12 in the lower section 10 of the plumb bob is the drum 13 on which is wound the lower end of the plumb bob suspending cord 9, said drum 13 having a transverse opening 14 near one end, through which the end of the cord 9 may be secured. This drum 13 has one end 15 rotatably positioned in a socket 16 provided therefor in one side of the lower section 10 of the plumb bob and opening into the well 12 thereof. This end 15 of the drum 13 has an annular channel 17 provided therein, within the socket 16 so that the pointed lower end 18 of the stud 19, may engage in the annular channel 17 and thus prevent longitudinal movement of the drum 13 without interfering with rotation thereof. This stud 19 has a threaded upper end 20 of larger diameter threading in the interiorly threaded vertical socket 21 which extends downwardly from the upper end of the lower section 10 and communicates at its lower end with

the non-threaded transverse socket 16, previously mentioned. This threaded upper end 20 of the stud 19 has also a transverse groove 22 in its upper face whereby the stud 19 may be readily turned and adjusted in the threaded socket 21, as desired.

The drum 13 has its opposite end 23 considerably increased in diameter and rotatable in a socket 24 opening on the outer face of the lower section 10 at a point diametrically opposite the transverse socket 16. The socket 24 is arranged

concentrically of the drum 13 and serves as the opening through which the drum 13 is inserted in the plumb bob lower section 10 or removed therefrom. The end 23 of the drum 13 has a series 5 of concave depressions 25 in its periphery to provide for locking the drum 13 automatically against casual rotation by seating of the lower convex end 26 of a locking pin 27 working in the smooth vertical socket 28 above the end 23 of the 10 drum 13 and in the lower section 10 of the plumb bob. This locking pin 27 is resiliently retained in its lowermost position by an expansion spring 29 resting in the upper end of the socket 28 and bearing on the upper end of the locking pin 27, 15 a small central projection 30 extending upwardly from the locking pin 27 into the spring 29. The end 23 of the drum 13 has a pair of small sockets 31 extending inwardly from the outer face thereof at diametrically opposite points to receive the 20 studs 32 projecting from one flat longitudinal edge 33 of the key 34 which is employed for turning or rotating the drum 13 and thus adjusting the plumb bob on the suspending cord 9 therefor by winding more of the cord 9 onto the drum 13 within the well 12 or unwinding the cord 9 25 from said drum 13, the drum 13 being rotatable in either direction by means of the key 34. When the upper section 6 and lower section 10 of the plumb bob are assembled, the upper end of the 30 lower plumb bob section 10 engages firmly against the lower face of the upper section 6, around the depending central portion 7 thereof. Furthermore, the spring 29 is compressed when the sections 6 and 10 are assembled and the locking pin 35 27 is thus resiliently retained in one of the depressions 25. By means of the key 34, the locking pin 27 is forced out of the depressions 25 and the end 23 of the drum 13 rides beneath the locking pin 27 as the drum 13 is rotated by the key 34, 40 until the drum 13 is properly adjusted when the locking pin 27 is then permitted to automatically seat itself in the depressions 25 brought to position beneath the same and the key 34 then removed until again required for use, the outer face 45 of the end 23 of the drum 13 remaining flush with the face of the plumb bob through which it extends, at all times, thus eliminating the necessity of having parts projecting from the face of the plumb bob.

50 As the construction of the device has thus been described in detail, brief reference is now had to its use and modus operandi: The sections 6 and 10 of the plumb bob may be readily secured together after the removable and adjustable parts 55 have been properly positioned in the lower section 10. The plumb bob may be readily adjusted along the suspending cord 9 therefor by employing the key 34 and when adjusted and the key 34 released, the locking key 27 will again automatically seat 60 in one of the depressions 25 and serve to firmly retain the plumb bob in its adjusted position on the suspending cord 9.

From the foregoing description taken in connection with the accompanying drawing, it will 65 be manifest that an adjustable plumb is provided that will fulfill all the necessary requirements of such a device but as many changes could be made in the above description and many apparently widely different embodiments of my invention 70 may be constructed within the scope of the appended claims without departing from the spirit or scope thereof, it is intended that all matters contained in the said accompanying specification and drawing shall be interpreted as illustrative and not in a limitative or restrictive sense.

Having thus described my invention, what I claim as new and desired to secure by Letters Patent is:—

1. An adjustable plumb including upper and lower plumb bob sections removably secured upon one another; a drum extended transversely in the lower section and rotatable therein having one end exposed and terminating flush with the outer surface of said lower section; a suspending cord carried on said drum and extending upwardly through the upper section of the plumb bob; means engaged with one end of said drum to prevent longitudinal movement thereof without interfering with rotation of said drum; means at the other end of the said drum to lock the same in adjusted position and prevent further accidental rotation thereof; and means for removably engaging the exposed end of said drum to alter the adjustment of said plumb bob on the suspending cord by rotating the said drum. 80
2. An adjustable plumb including a plumb bob formed of an upper section with a depending threaded central portion and a central longitudinal opening; a lower plumb bob section threaded on the depending portion of said upper plumb bob section; a drum extended transversely in the said lower section; means associated with one end of said drum to prevent longitudinal movement thereof without interfering with rotation of said drum; a suspending cord secured to and adapted to wind on said drum; said suspending cord extending upwardly through the central longitudinal opening in said upper section; the other end of said drum being enlarged and provided with depressions in its periphery; yieldably mounted 90 means within said lower section for automatic seating in one of said depressions to hold said drum against accidental and unauthorized rotation; said enlarged end having openings in its outer face; and a key provided with projections 95 for engagement in said last mentioned openings, whereby said drum may be rotated by said key and the plumb bob thus adjusted longitudinally of said suspending cord. 100
3. An adjustable plumb including upper and lower plumb bob sections, said upper section having a depending portion and a vertical central opening, a well centrally in the top of said lower section adapted to receive the depending threaded portion of said upper plumb bob section, an axial bore through one wall of said lower section, below the depending portion of said upper section, into said well and a seat in the opposite side of said well in alignment therewith, a vertical socket extending from said seat to the top edge 110 of said lower plumb bob section, a rotatable drum projecting transversely through said axial bore across said well and into said seat, an annular channel in the end of said drum resting in said seat, a stud in said socket whose lower end is 115 adapted to extend into said annular channel to prevent unauthorized longitudinal displacement of said drum, a suspending cord winding on said drum and extending upwardly through the vertical central opening in said upper section, means 120 for rotating said drum and means for holding said drum in adjusted position. 125
4. An adjustable plumb including upper and lower plumb bob sections, said upper section having a depending threaded portion and a vertical central opening, a well centrally in the top of said lower section adapted to receive the depending threaded portion of said upper plumb bob section, an axial bore through one wall of said lower section, below the depending portion of said 130
5. An adjustable plumb including upper and lower plumb bob sections, said upper section having a depending threaded portion and a vertical central opening, a well centrally in the top of said lower section adapted to receive the depending threaded portion of said upper plumb bob section, an axial bore through one wall of said lower section, below the depending portion of said 135
6. An adjustable plumb including upper and lower plumb bob sections, said upper section having a depending threaded portion and a vertical central opening, a well centrally in the top of said lower section adapted to receive the depending threaded portion of said upper plumb bob section, an axial bore through one wall of said lower section, below the depending portion of said 140
7. An adjustable plumb including upper and lower plumb bob sections, said upper section having a depending threaded portion and a vertical central opening, a well centrally in the top of said lower section adapted to receive the depending threaded portion of said upper plumb bob section, an axial bore through one wall of said lower section, below the depending portion of said 145
8. An adjustable plumb including upper and lower plumb bob sections, said upper section having a depending threaded portion and a vertical central opening, a well centrally in the top of said lower section adapted to receive the depending threaded portion of said upper plumb bob section, an axial bore through one wall of said lower section, below the depending portion of said 150

upper section, into said well and a seat in the opposite side of said well in alignment therewith, a threaded socket extending from said seat to the top edge of said lower plumb bob section, a second smooth socket rising from said axial bore to the top edge of said lower plumb bob section, a rotatable drum projecting transversely through said axial bore across said well and into said seat, an annular channel in the end of said drum resting in said seat, a stud in said socket whose lower end is adapted to extend into said annular channel to prevent unauthorized longitudinal displace-

ment of said drum, said drum also having a plurality of concave depressions in its opposite end within said axial bore, a spring urged locking pin in said second smooth socket to selectively engage one of said concave depressions to retain said drum in the desired rotative adjustment, a suspending cord winding on said drum and extending upwardly through the vertical central opening in said upper section and a removable key for engagement with said drum whereby it may be rotated. 80 85
